US0D1046293S

(12) **United States Design Patent** (10) **Patent No.:** **US D1,046,293 S**
(45) **Date of Patent:** **** Oct. 8, 2024**

(54) **RAZOR HANDLE**

(71) Applicant: **The Gillette Company LLC**, Boston, MA (US)

(72) Inventor: **Christopher Ramm**, North Attleboro, MA (US)

(73) Assignee: **The Gillette Company LLC**, Boston, MA (US)

(**) Term: **15 Years**

(21) Appl. No.: **29/886,518**

(22) Filed: **Mar. 9, 2023**

Related U.S. Application Data

(62) Division of application No. 29/829,962, filed on Mar. 9, 2022, now Pat. No. Des. 984,744, which is a division of application No. 29/760,717, filed on Dec. 3, 2020, now Pat. No. Des. 950,153.

(57) **CLAIM**

The ornamental design for a razor handle as shown and described.

DESCRIPTION

FIG. 1 is a front perspective view of a design of a razor handle of the present invention;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

In the drawings, the broken lines illustrate portions of the razor handle and form no part of the claimed design.

1 Claim, 5 Drawing Sheets
